(57) **CLAIM**

The ornamental design for an anti-overflow double-sided cutting board, as shown and described.

DESCRIPTION

FIG. 1 is a perspective view of an anti-overflow double-sided cutting board showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is another perspective view thereof; and,

FIG. 9 is a cross sectional view taken along the line A-A of FIG. 7.
